UNITED STATES PATENT OFFICE.

WILLIAM WHARTON, JR., AND EDWARD SAMUEL, OF PHILADELPHIA,
PENNSYLVANIA, ASSIGNORS TO WILLIAM WHARTON, JR., & COMPANY, (LIMITED,) OF SAME PLACE.

DESIGN FOR A RAILWAY-RAIL.

SPECIFICATION forming part of Design No. 16,764, dated June 29, 1886.

Application filed March 16, 1886. Serial No. 195,474. Term of patent 14 years.

To all whom it may concern:

Be it known that we, WILLIAM WHARTON, Jr., and EDWARD SAMUEL, both citizens of the United States, residing in Philadelphia, Pennsylvania, have invented a certain new and original Design for Railway-Rails, of which the following is a specification.

Our design for a railway-rail is fully illustrated in the accompanying drawing, the view 10 in which is a transverse section showing in outline our railway-rail.

Our design comprises a vertical web, *a*, with two flanges, *b* and *d*, their upper parts projecting laterally and being of different heights and different widths, as shown, and 15 having between them a groove, *e*. The flange *d* has at its outer edge, on the

under side, a lip, *f*. Between the flanges and web, on the under side, are curved shoulders *ss*.

We claim—

The herein-described design for a railway-rail, having in transverse section the outline illustrated, and comprising the web *a*, flanges *b* and *d*, rib *f*, and shoulders *ss*, substantially as shown and set forth.

In testimony whereof we have signed our names to this specification in the presence of two subscribing witnesses.

WILLIAM WHARTON, JR.
EDWD. SAMUEL.

Witnesses:

JOSEPH H. KLEIN,
HARRY SMITH.
